a corporation of Delaware

Application November 12, 1941, Serial No. 418,671

12 Claims. (Cl. 250—13)

1

This invention relates to improvements in antenna coupling devices, and in particular to such devices as applied to enemy aircraft identification by friendly aircraft or by antiaircraft stations. A typical system to which the invention is applicable has been disclosed in the copending application of H. G. Busignies, Serial No. 417,151, filed October 30, 1941, and entitled "Aircraft identifier."

Systems have been devised, especially in the police radio field for utilizing one antenna for both transmitting and receiving. Such simultaneous operation can be attained when both transmitting and receiving equipment is operating on slightly different frequencies; and, if only one frequency be used, switch-over from transmitter to receiver may be accomplished by ordinary relay apparatus.

In connection with the use of impulse-energy-operated systems for obstacle identification purposes on the ground or in aircraft, it may be desirable to use only one antenna for transmission and reception on the same frequency with changeover as rapid as a few microseconds, or even a fraction of a microsecond. It is well-known that impulse systems of the nature referred to involve the transmission of relatively large amounts of power and detection of relatively weak signals. As a result, previous switch-over methods and systems may not be satisfactory in impulse systems of this character.

Accordingly, it is an object of the invention to provide improved means for enabling concurrent transmission and reception on a common antenna. Another object is to provide improved means for permitting alternate transmission and reception of radiant energy of substantially the same carrier frequency on a single antenna. A further object is to provide improved switching means. It is a more specific object to provide improved means permitting the use of a single antenna for transmission of impulse energy and detection of a reflection thereof.

Other objects and various further features of novelty and invention will hereinafter be pointed out or will occur to those skilled in the art from a reading of the following specification in conjunction with the drawing included herewith. In said drawing—

Fig. 1 is a schematic block diagram illustrating an embodiment of the invention; and

Figs. 2 and 3 show alternative preferred forms of portions of the embodiment shown in Fig. 1.

As above indicated, in systems employing transmission and reception of impulse energy characterized by the same carrier frequency, certain difficulties may arise in the use of present switching devices, which operate mechanically or otherwise to switch transmission or receiving apparatus to an antenna. It is accordingly

2

deemed desirable for this purpose to employ permanently coupled transmission lines between the antenna and both the transmitter and receiver, and to make use of additional circuit elements alternately to block each of these transmission lines.

It is known that a resonating section of transmission line, $\frac{1}{4}$ wave length long, short-circuited at one end, and coupled to another transmission line may introduce substantial voltages into the latter. If the resistance of the coupled section is negligible, these voltages may be so large as effectively to block or prevent the passage of power along the transmission line at the point where the section is coupled. In accordance with features of the invention I propose to utilize this blocking effect of a $\frac{1}{4}$ wave short-circuited line for above-indicated antenna switching purposes.

A preferred embodiment of the invention as thus applied is shown in Fig. 1 where a single antenna 10 is employed for transmission and reception. Antenna 10 may be directly coupled as shown to a transmitter 11 by a suitable transmission line 12 and to a receiver 13 by line 14. In order alternately to block transmission lines 12 and 14, short-circuited coupled sections 15 and 16, respectively are provided coupled to each of these lines.

As indicated above it is expressly contemplated that my invention will be applicable to concurrent transmission and reception of impulse energy, reception being operative during intervals between transmission of individual impulses. Due to the extremely rapid rate of switch-over required, however, mechanical systems for varying the resonance, and hence blocking effect, of coupled sections 15 and 16 are deemed inappropriate. Accordingly, in accordance with the invention I propose to employ a vacuum-tube controlled circuit 17, 18 in each section and coupled thereto as shown.

Inasmuch as it is contemplated that line 14 will be open most of a cycle of transmission and reception, the reactance offered by tube circuit 18 preferably normally maintains coupled section 16 in a detuned state, whereby substantially no blocking of received energy results. A very short instant before the transmission of an impulse, tube circuit 18 is appropriately energized as to present such reactance to coupled section 16 that the section will resonate and thus prevent any transmitted energy being dissipated in line 14. This condition of resonance is preferably maintained for the duration of the transmitted impulse and a very short instant thereafter in order to be absolutely sure of blocking reception of impulses as they are transmitted. Since it is desired to make line 12 conductive while line 14 is not, tube circuit 17 for coupled section 15 is

preferable operative in a sense inverse to circuit 18, as will be clear.

The circuit of Fig. 1 shows schematically how the desired relation of blocking and passing effects of coupled sections 15 and 16 may be obtained. In accordance with known practice an impulse generator 19 may be employed in the generation of impulses to be transmitted and at the same time for energizing an appropriate blocking circuit 20 to assure that the receiver is inoperative as individual impulses are being transmitted. As indicated, blocking circuit 20 may supply a blocking signal of slightly greater duration than that of the transmitted impulses. Suitable means for generating such a signal has been disclosed in the copending application of E. Labin, Ser. No. 386,282, filed April 1, 1941, and entitled "Pulse modulation system." In the form shown, in order to assure that transmitted impulses may fall within the above-mentioned blocking interval, appropriate time delay means 21 may be included in the line energizing transmitter 11.

In accordance with a feature of the invention I employ energy supplied by blocking circuit 20 to control the alternate resonant and non-resonant conditions of coupled sections 15 and 16. As mentioned, the output of blocking circuit 20 is a series of impulses of slightly greater duration than the transmitted impulses. In the form shown, these blocking impulses may be applied directly to tube circuit 18, and means (not shown) may be provided to control or adjust the magnitude of these impulses to assure resonance in section 16 while such impulses are being supplied. In order to energize tube circuit 17 appropriately, an inverter circuit 22 of known construction may be employed to feed circuit 17 with blocking energy inverse to that which is being supplied circuit 18. Thus, coupled section 15 may be maintained normally in a condition of resonance; that is, during intervals between transmission of impulses, to prevent received energy from being dissipated in transmission line 12, as will be clear.

In Fig. 2 I show a preferred embodiment of a possible tube circuit for performing the functions above mentioned in connection with circuits 17 and 18. In this embodiment a short-circuited quarter-wave length section 23, which may correspond to section 15 or 16 in Fig. 1, may be rendered alternately resonant and non-resonant by corresponding alternate substantial application and removal, as the case may be, of a shunt impedance supplied as the output of tube 24. This function of tube 24 is obtained in accordance with blocking signal energy, which may be supplied in the manner above indicated, to the input 25 of the device. In a well-known manner, blocking, or resonance exciting, energy is applied over a coupling condenser 26 and across a resistance, which in the form shown includes a resistor 27 and a portion of a bias-control potentiometer 28.

Turning in more detail to a consideration of tube connections to coupled section 23, output of tube 24, which in the form shown includes a cathode, control grid, screen grid, and anode elements, may be applied to the section at points 29, 30, the voltages at these points being 180° out of phase. Both supply lines include blocking condensers 31, 32, and one of these lines further includes a resistor 33. Resistor 33 is preferably of such a magnitude that the value of the RC network formed by resistor 33 and

the grid-cathode capacitance of tube 24 will displace the phase of the radio-frequency grid voltage substantially 90°, with respect to that at point 29. Inasmuch as the plate current of tube 24 is in phase with the voltage applied to the control grid, this current leads the voltage at point 30, because voltages at points 29, 30 are 180° out of phase, as will be recalled. It thus becomes clear that radio frequency plate current fed into section 23 through blocking condenser 32 may produce an effective shunt capacity across the section, since voltage and current, as above indicated, are substantially 90° out of phase.

15 This effective shunt capacity may vary with the amplification or output of the tube. Accordingly, appropriate adjustment, say of grid bias by means of potentiometer 28, may control the magnitude of shunt reactance across points 29, 30 to a desired degree, depending on the magnitude of blocking signal applied at input 25. As desired, radio frequency chokes 34, 35 may be provided in the input and output circuits of tube 24 to isolate grid and plate supply respectively, and a screen grid voltage may then be supplied over a resistor 36.

The unit shown in Fig. 2 would preferably normally be adjusted so that coupled section 23 would be detuned when no signal is supplied to input 25. Upon application of the signal of fixed amplitude, the resultant reactance across the section would be such as to resonate the section, thus preventing flow of current in the transmission line to which the section is coupled, as will be clear.

It is further clear that in an alternative embodiment the physical length of section 23 may be so designed that the large effective shunt capacity due to the circuit of Fig. 2 when a signal is applied will detune rather than resonate the section, and so that the normal effective shunt reactance offered by the circuit when no signal is applied will permit section 23 to resonate. Thus, when a blocking impulse is impressed at input 25, section 23 may be detuned to permit passage of energy along the line to which it is coupled; and when the blocking impulse is removed, a blocking effect results on the line. Thus, the identical blocking impulse, which 40 served in the first-discussed case to produce a blocking action on the line to which the section was coupled, may also serve in this alternative embodiment to pass energy along a line; and, during the interval no blocking signal is applied, the former section may be detuned to pass energy, whereas the latter may resonate and block. It would, therefore, be clearly possible in an alternative embodiment of the circuit of Fig. 1 to employ a coupled-section circuit of the former nature coupled say to line 14, and one of the latter nature coupled to line 12. In such case, the blocking signal obtained from circuit 20 could be supplied directly to tube circuits 17 and 18, and there would be no need for inverter 22.

In Fig. 3 I show a further preferred embodiment of possible circuits 17 or 18. The circuit employed makes use of the property of a $\frac{1}{2}$ wave-length line to present an impedance varying in phase at one end of the line when a shunt resistance at the other end is varied.

In the form shown a $\frac{1}{2}$ wave-length line 37 may be connected to a coupled section 23' between points 29', 30' in a manner which may be similar to corresponding connections shown in

Fig. 2. Line 37 is shown terminated by a shunt inductance 38 and by the respective outputs of two amplifier tubes 39, 40 connected in tandem. Input to tubes 39, 40 may be supplied in a manner analogous to such supply in the circuit of Fig. 2, as will be clear. Inductance 38 is preferably so selected as to have a value permitting resonance with the internal capacities of tubes 39 and 40, for a purpose that will readily be understood.

As in the case of Fig. 2 the gain of tubes 39 and 40 may be controlled by appropriate adjustment of a bias-control potentiometer 28'. It will be clear that as bias of tubes 39 and 40 is thus varied, these tubes may be made to operate within a range from cut-off to saturation, and that concurrently the effective shunt impedance offered by the plate circuits of these tubes may vary from a resistive value of $Q/\omega C$ as a maximum to a value approximately equal to

$$\frac{1}{G_{m39}} + \frac{1}{G_{m40}}$$

as a minimum, where G_{m39} and G_{m40} are the mutual conductance values of tubes 39 and 40, respectively. It is considered that such a variation will be sufficient to produce a large enough phase variation at the 29', 30' end of line 37 to tune and detune coupled section 23' completely.

The effective shunt impedance presented by the plates of tubes 39 and 40 may be varied by varying the voltage applied to the grids, as introduced across resistor 27' and a portion of potentiometer 28'; and the exact point of operation, as above-indicated, may be determined by adjustment of potentiometer 28'. I prefer to make such adjustment so that plate current will flow in tubes 39 and 40 when no signal is applied. Under this condition section 23' would be non-resonant or detuned, and no blocking effect would be obtained in the transmission line to which section 23' is coupled. Since section 23' is thus detuned, substantially no current will be induced therein from the line to which it is coupled, and consequently no loss will ensue, due to the low resistance introduced by tubes 39 and 40 being coupled to line 37.

When, thereafter, a blocking signal characterized by a negative impulse is applied, tubes 39 and 40 will be cut off, thus permitting section 23' to resonate with the reactance presented by the $\frac{1}{8}$ wave-length line terminated by the parallel shunt combination of inductance 38 and the internal capacities of tubes 39 and 40. Under this condition no flow of current will take place in the transmission line to which section 23' is coupled, but a high circulating current will be present in the circuit comprising section 23', line 37, and the tuned circuit made up of inductance 6 and the tube capacities.

It will be recalled from the discussion of Fig. 2 that the physical length of section 23 may be designed to resonate when the effect of the tube circuit across points 29, 30 is substantially open circuit and to detune when the effective shunt capacity is large. An analogous variation may be made in the circuit of Fig. 3 by also appropriately designing the length of the section (23'). In the thus modified form of Fig. 3 section 23' could be made to resonate normally, that is, while no blocking signal is applied to the input, and to detune when a negative blocking impulse is applied. In such case, then, it would be possible to use say the first-described embodiment of Fig. 3 to block and open line 14, and the latter to

perform the inverse function with regard to line 12, as will be clear. It thus appears that coupled sections 15 and 16 could be made alternately to operate in inverse senses upon application of the same negative blocking signals simultaneously to both tube circuits 17, 18. Naturally, of course in this proposal, as in the case of the corresponding proposal in connection with Fig. 2, there would be no need for inverter 22.

10 Although I have described the embodiment shown in Fig. 3 as operative upon application of a negative blocking impulse, it is clear that it may also operate upon application of positive impulses. In this case, tubes 39, 40 would normally be biased below cut-off, and application of blocking impulses of correct magnitude could be made either to resonate or detune section 23', depending upon the designed physical length thereof in view of the foregoing discussion.

20 I have purposely omitted any reference in this disclosure as to what point along the section the tube circuit should be inserted, inasmuch as the particular connection point is considered relatively unimportant. I prefer, however, to employ

25 some point along the section generally intermediate the open and shorted ends. The reason for such preference is clear. If the effective shunt capacity were inserted near the shorted end, the voltage shunted would be relatively low and practically the only effect of varying shunt capacity

30 would be in the nature of a trimming action, as disclosed for example in Patent 2,259,510, granted October 21, 1941, to A. Alford, and entitled "Coupling arrangements for high frequency transmission systems." On the other hand, at resonance, voltages across the open end are a maximum and may be so great as to produce deleterious or undesirable effects on the tube circuits. Accordingly, as indicated, some intermediate position is preferred.

40 Although I have described my invention in particular detail in connection with transmission and reception on a common antenna, it is clear that the antenna is merely illustrative, for it may be considered representative, for example, of a transmission line or other network in conjunction with which concurrent transmission and reception are desired. It is also clear that many modifications, additions, and omissions may be made within the scope of the invention.

What I claim is:

1. A radio system including impulse transmitter means, antenna means, receiver means responsive to reflections of impulse energy transmitted by said transmitter means, a first transmission line connecting said transmitter means to said antenna means, a second transmission line connecting said receiver means to said antenna means, impedance varying means spaced 55 from each of said transmission lines and respectively coupled thereto and means controlled by said impulse transmitter means alternately rendering said impedance varying means effective on their respective transmission lines to render said first and then said second transmission lines ineffective to pass such impulse energy.

2. A radio system including transmitter means transmitting periodically recurrent impulse energy, antenna means, receiver means responsive to such impulse energy, means connecting said transmitter means to said antenna means, means connecting said receiver means to said antenna means, and means spaced from said transmitter and receiver means respectively but coupled thereto controlled by said transmitter means for

alternately rendering said first and said second-mentioned connecting means ineffective to pass such impulse energy in accordance with said periodic recurrence.

3. An impulse energy transmission and reception system including an impulse transmitter, a receiver, an antenna, connecting means connecting said transmitter and said receiver to said antenna, and control means rendering said connecting means ineffective alternately to connect said transmitter and said receiver to said antenna, said control means including a relatively short section of transmission line coupled to said connecting means and short-circuited at one end of said section, and means controlled by said transmitter periodically varying the effective shunt reactance between points on each side of said section.

4. An impulse energy system according to claim 3, in which said connecting means includes a transmission line coupling said transmitter and said antenna, and a transmission line connecting said receiver and said antenna, and in which said control means includes one said section coupled to said first transmission line and another said section coupled to said second transmission line.

5. An impulse energy system according to claim 3, in which said connecting means includes a transmission line coupling said transmitter and said antenna, and a transmission line connecting said receiver and said antenna, and in which said control means includes one said section coupled to said first transmission line and another said section coupled to said second transmission line, and wherein said periodically varying means is connected between points on each side of each said section and periodically varies the effective shunt reactance between said points on said one section in a sense inverse to such periodic variation between said points on said other section.

6. The method of varying the resonant condition of a $\frac{1}{4}$ wave-length transmission line having one end short-circuited, which comprises connecting one end of a $\frac{1}{8}$ wave-length line between points on each side of said transmission line and varying a resistance connected across the other end of said $\frac{1}{8}$ wave-length line.

7. The method of transmitting impulse energy and receiving reflections thereof on a single antenna connected to an impulse transmitter and a receiver, there being a section of transmission line inductively coupled to the line connecting the transmitter and antenna and another such section inductively coupled to the line connecting the antenna and receiver, which method comprises resonating the section of transmission line inductively coupled to the line connecting the receiver and antenna during transmission of impulse energy, and resonating the section of transmission line inductively coupled to the line connecting the transmitter and antenna during intervals between said transmission of impulse energy.

8. The method of transmitting impulse energy and receiving reflections thereof on a single antenna connected to an impulse transmitter and a receiver, there being a section of transmission line inductively coupled to the line connecting the transmitter and antenna and another such section inductively coupled to the line connecting the antenna and receiver, which method comprises resonating the section of transmission line inductively coupled to the line connecting the receiver and antenna during transmission of im-

pulse energy while detuning the section of transmission line inductively coupled to the line connecting the transmitter and antenna, and resonating said second-mentioned section while detuning said first-mentioned section during intervals between said transmission of impulse energy.

9. In a system for controlling energy flow along a transmission line, a short-circuited quarter wave-length section inductively coupled to said line, means including vacuum tube control means connected across said section and forming a variable effective shunt reactance across said section for alternately tuning and detuning said section in accordance with signals applied to said vacuum tube control means, said control means including a vacuum tube having a cathode, a control grid, and an anode, means connecting said grid to one side of said section, and means connecting said anode to the other side of said section, said first-mentioned and said second-mentioned connecting means each including means effecting substantially a relative 90° phase displacement between current in each said connecting means.

10. In a system for controlling energy flow along a transmission line, a short-circuited quarter wave-length section inductively coupled to said line, means including vacuum tube control means connected across said section and forming a variable effective shunt reactance across said section for alternately tuning and detuning said section in accordance with signals applied to said vacuum tube control means, said control means including a pair of vacuum tubes, each of said vacuum tubes including a cathode, a control grid, and an anode, a $\frac{1}{8}$ wave-length line having one end connected across said section and each side of the other end connected to the anode of one of said vacuum tubes, means connecting the grids of said tubes, and an impedance bridging said other end of said $\frac{1}{8}$ wave-length line, said impedance being such as to form with internal impedances of said tubes a resonant circuit.

11. In a system for controlling radio frequency energy flow along a transmission line, a short-circuited line section inductively coupled to said transmission line, and control means connected across said section and forming a variably reactive shunt impedance across said section for tuning and detuning said section in accordance with variation of said control means, said control means including a $\frac{1}{8}$ wave-length line having one end connected across said section, and means producing a variable resistance effect across the other end of said $\frac{1}{8}$ wave-length line.

12. A radio system including transmitter means for transmission at a given carrier frequency, antenna means, receiver means responsive to said given carrier frequency, a first transmission line connecting said transmitter means to said antenna means, a second transmission line connecting said receiver means to said antenna means, impedance varying means spaced from each of said transmission lines and respectively coupled thereto, and means responsive to energy from said transmitter for alternately rendering said impedance varying means effective on their respective transmission lines to render said first and the said second transmission lines ineffective to pass energy of said given carrier frequency.

ROSS B. HOFFMAN.
